UNITED STATES PATENT OFFICE.

WILHELM SCHWENK, OF NEW YORK, N. Y.

DESIGN FOR A WALL-BRACKET.

SPECIFICATION forming part of Design No. 31,042, dated June 20, 1899.

Application filed May 16, 1899. Serial No. 717,101. Term of patent 3¹/₂ years.

To all whom it may concern:

Be it known that I, WILHELM SCHWENK, a subject of the Emperor of Germany, residing at New York, in the county of New York and State of New York, have invented and produced a new and original Design for Wall-Brackets, of which the following is a specification, reference being had to the accompanying drawings, forming part thereof.

10 In the drawings forming part of this specification, Figure 1 is a plan or front view of a wall-bracket, showing my new design; and Fig. 2, a transverse section thereof on the line 2 2' of Fig. 1.

15 As shown in the drawings, the leading or material feature of my design consists of a back portion or plate A, having the form of a shield, which is provided with a front portion B of similar shape, having two transverse and oblong openings b and b' formed therein, the upper opening b being larger and deeper or wider than the lower opening b'.

20 The openings b and b', formed in the front portion B of the design, are provided with 25 corresponding doors or flaps C and C', hinged

to the bottom thereof and formed by cutting out said openings, and these doors or flaps are connected midway of their width with the back portion A by flexible straps D, and each of said doors or flaps is provided with 30 an ornamental front plate E similar in form thereto and having an ornamental border F.

The doors or flaps C and C' form pockets G, and at the bottom of the bracket and centrally thereof is a receptacle H, open at the 35 top and bottom, and above and at each side of said receptacle H are hooks K.

Having fully described my invention, I claim as new and desire to secure by Letters Patent—

40 The design for a wall-bracket as herein shown and described.

In testimony that I claim the foregoing as my invention I have signed my name, in presence of the subscribing witnesses, this 15th 45 day of May, 1899.

WILHELM SCHWENK.
